(57) **CLAIM**

The ornamental design for a fairing turbine panel, as shown and described.

DESCRIPTION

FIG. 1 is a top, front, left side perspective view of a fairing turbine panel, showing our new design;

FIG. 2 is a left, side elevation view thereof enlarged for ease of illustration, the right side elevation view being a mirror image;

FIG. 3 is a front elevation view thereof; and,

FIG. 4 is a top plan view thereof.

The broken lines illustrate portions of the fairing turbine panel that form no part of the claimed design.
